UNITED STATES PATENT OFFICE.

DANIEL M. LESTER, OF NORWICH, CONNECTICUT.

ENVELOPE-MACHINE.

SPECIFICATION forming part of Letters Patent No. 226,331, dated April 6, 1880.

Application filed January 17, 1880.

To all whom it may concern:

Be it known that I, DANIEL M. LESTER, of 5
Norwich, Connecticut, have invented a new
and useful Improvement in Counting Attach-
ments for Envelope-Machines, of which the
following is a specification.

My improvement relates to attachments to
envelope-machines for the purpose of counting
and arranging the envelopes in packs of
ten twenty-five as they are passed out of the folding
and gumming machine; and it consists in
certain devices, to be hereinafter described
and claimed, whereby the receiver is shunted
to first one side and then the other, as often
as twenty-five envelopes are delivered into
said receiver; and also in a certain arrange-
ment for preventing a count being made un-
less an envelope passes over.

The following is a description of the figures
of the drawings, in which like letters refer to
the same parts.

Figure 1 is a perspective view of the entire
attachment. Fig. 2 is a vertical cross-section,
showing the principal working parts of the
machine. Fig. 3 is a detailed view of a part
of the serpentine cam. Fig. 4 is a detailed view
of the check arrangement for the pawl.
Fig. 5 shows packs of envelopes as deposited
in the receiver.

A is the platform of the attachment, which
is connected with an ordinary envelope-folder,
which, of course, need not be shown in the
drawings.

B is the receiver, into which the envelopes
are automatically placed in packages of twenty-
five as delivered from the folder.

C is a weighted slide to hold the packs in
place until removed.

D is a plate which forces each envelope
separately into its place in the pack forming
in the receiver.

E is a cam upon shaft F, which operates
upon the short end of the lever D', which car-
ries forward and backward the push-plate D.

G is a second cam upon the same shaft for
operating a forked lever, K. This last is
jointed to and reciprocates a second lever, I,
which carries at its outer end a pawl, J, for
operating the circular rack H. This rack has
fifty teeth, and rotates once for each two packs
of envelopes carried to place in the receiver.

This circular rack has connected to it, or in-
tegral with it, as may be preferred, a serpen-
tine cam whose direction is changed at the
two points e and f.

In the groove of the serpentine cam is a pin,
g, connected to a jointed lever, L M, for shunt-
ing the receiver from side to side, as stated
above. One end of L is secured to the frame
of the machine, and serves as a fulcrum. The
other end is secured to the under side of the
receiver B.

k, Fig. 2 is a coil-spring to force back pawl-
arm I.

Fig. 4, a is a short lever attached to the rock-
shaft N, which carries a pendent plate or pro-
jection, h, lying directly in the path of the
envelopes. This short lever a is pivoted to
an upright, b, which, in its turn, is jointed to
an arm, d, at c. This arm d carries, bent at 70
right angles to it, a check-plate, o, which passes
directly under the pawl J, filling up the tooth
of the rack, so that said pawl, when moved
forward, will slide over without turning for-
ward the rack H. Whenever the top of an 75
envelope, in its passage forward, forces aside
the plate h, this plate o is taken out of the
path of the pawl, which can then perform its
function of turning forward the circular rack
H one-fiftieth of its circumference.

The handle at left of Fig. 1 is merely for
convenience of operating the machine by hand.

The operation of this machine is as follows,
viz: In practice F may be the usual driving-
shaft of the folding-machine, carrying the two 85
cams E and G. It will be readily seen that by
the revolution of the cam E the lever D' is re-
ciprocated, and through it the plate D pushed
forward with the envelope in front of it as
dropped from the folding-machine. The top of 90
this envelope, as it passes forward, forces for-
ward the plate h, which, through the interme-
diate mechanism above described, raises the
check-plate o out of the path of the pawl J,
which is operated by the smaller cam G 95
through levers K and I.

If by any means an envelope is not dropped
before the plate D, then the plate o is not re-
moved out of the path of pawl, and so no count
is made—that is to say, the rack is not moved 100
forward one tooth of the count of twenty-five.
As soon as the rack has turned forward twen-

ty-five teeth, or received twenty-five forward movements from the pawl above described, then the pin *g* is turned from its course by either the turn *e* or *f* in the path of the serpentine cam attached to the disk-rack *H* and moving with it.

It will be readily seen from the above that although the machine continues its revolutions and the plate *D* moves backward and forward, 10 yet the rack-wheel cannot go forward a single count until the top of a passing envelope forces forward the projection *h* and lifts the obstructing plate away from the pawl.

It will also be seen that as often as twenty-five envelopes are counted the pin *g* changes to one side by a turn or bend in the path of the serpentine cam, and, through its lever-connections, shunts or switches the receiver *B* an inch or so to one side. Thus while 15 the envelopes go forward in a direct line the receiver, as fast as twenty-five are passed through into it, slides an inch or so to right and left, and continues these movements. This leaves each package of twenty-five an 20 inch or so projecting either to right or left of the others. These packs can then be very rapidly and safely removed with no danger, to speak of, of being mixed with each other.

I am aware that it is not broadly new to 30 throw envelopes into packages of twenty-five (as they are fed forward) by means of alternately depressing the edges of the table, thus partially rotating it about a central axis; but this construction in the machines commonly 35 made for the market requires a somewhat complicated arrangement of parts; and it is to lessen the number of parts and difficulties of construction and simplify generally the counting-machine that I have devised means for 40 shunting the table from side to side in the same horizontal plane. This leaves the envelopes also standing horizontally, and thus lessens in practice the difficulty of removing each package without one envelope slipping from its 45 place.

I lay claim to no devices shown in Patent No. 151,158.

I am also aware that it is not broadly new to reciprocate a table in the same horizontal plane for the purpose of laying out sheets of 50 paper in piles of a certain number, and I therefore only lay claim to the new devices or instrumentalities by which I reciprocate the receiving-table of my envelope-machine.

I am also aware that devices are not broadly 55 new for preventing the count unless an envelope absolutely passes to its place, and I therefore do not claim, broadly, such devices.

What therefore I claim as my invention is—

1. In a counting attachment for envelope-machines, a horizontal receiver reciprocated to one side and the other in the same horizontal plane by a lever operated by a serpentine cam attached to a rack-wheel of fifty teeth, said rack-wheel being automatically 60 moved forward through the communicated revolutions of the operating-shaft.

2. In combination with a reciprocating push-plate, *D*, of an envelope-counting machine in which the receiving-bed reciprocates in a horizontal plane only, a projection, *h*, hanging down in the path of the envelopes and operated by each as it passes, said projection *h* being upon a shaft which, through lever-connections, operates to remove a check-plate from 75 the path of the pawl, which forces forward a circular rack and serpentine cam.

3. In an envelope-counting machine in which the bed moves only in a horizontal plane, a rack-wheel of fifty teeth, carrying a 80 serpentine cam with two breaks or bends, *e* and *f*, in its path, and a pin moving in its groove and connected with a jointed lever to reciprocate sidewise the receiver for the envelope-packs.

DANIEL M. LESTER.
